(57) **CLAIM**

We claim the ornamental design for a cable management apparatus for partitions, as shown and described.

DESCRIPTION

FIG. 1 is a perspective view of a cable management apparatus for partitions, embodying our design;

FIG. 2 is a front view of FIG. 1;

FIG. 3 is a rear view of FIG. 1;

FIG. 4 is a side view of FIG. 1; and,

FIG. 5 is a top view of FIG. 1.

The dashed lines in FIGS. 1-5 are to show the environment and do not form a part of the present invention.

The claimed design is shown broken away to indicate indeterminate length.
